UNITED STATES PATENT OFFICE

LAURENS VAN HÜLST, OF MERSEBURG, GERMANY

TILT FOR COVERING OPEN TRUCKS

Application filed February 1, 1929, Serial No. 336,732, and in Germany March 8, 1926.

The invention relates to tilts for covering open trucks, particularly railway trucks, in place of the usual canvas tilts. These canvas tilts are expensive and under repeated use, sustain a considerable amount of wear which soon renders them leaky so that they no longer fulfill their purpose.

In order to avoid the defects of canvas tilts, use is made according to the invention of a paper tilt, said covering sheet being made watertight and fireproof by suitable impregnation and being protected against tearing at the edges.

In respect of impermeability and proof against fire and also in respect of safety in railway operation, this tilt must be regarded as quite equivalent to a canvas tilt. Although as a rule it can only be used once for covering railway trucks, it is however so low in first cost as still to form a considerably cheaper truck cover than canvas tilts.

The tilt may be rendered watertight and fireproof by coating it with bitumen of high melting point. The coating may be applied by brushing or pressure, the strength of the paper—ordinary packing paper in particular—being thereby considerably increased.

The tilt is preferably made of two sheets of paper with an intermediate layer of bitumen, the outer sides of the tilt being also provided with a coating of bitumen.

On the other hand, it is new to employ for railway purposes watertight and fireproof paper tilts, the width of the cover or tilt being less than the width of the body of the railway truck. In order to enable the ends of these tilts to be fastened as securely as possible to the truck, the invention provides for the edges of the sheets of paper to be turned over and thus secured against tearing. In addition, the edges can be strengthened by the insertion of wires or by the application of wooden battens.

In order to make provision for the sufficient cooling of briquettes—for the covering of which the tilts are mainly intended—and to afford an outlet for the water vapour thereby liberated, the tilts according to the invention may be so designed that the rectangular sheet of paper of which the tilt is composed,

is somewhat smaller in dimensions than the floor area of the truck, so as to leave narrow uncovered gaps on all four sides of the truck, or on the two longer sides of same.

According to my invention, a strip of 55 waterproof paper is of a length sufficient to overlie the ends of a car or truck body, and of less width than the distance between the sides, this paper being reinforced by turning the ends inward, and such inturned ends 60 may encase reinforcing battens or wires, which will not only stiffen the ends, but will also prevent tearing of the ends and assist in coiling the strip for transportation when not used as a cover.

In the accompanying drawings,—

Figure 1 is a plan view.

Figure 2 is a transverse section.

Figures 3 and 4 are detail views.

Referring to the drawings, the body 1 of the truck is provided at intervals with eyes or staples 5, 5' which are located to be of easy access and in practice they may be stake sockets.

The tilt 2 consists of a sheet of waterproof and fireproof paper of less width than the distance between the side boards of the body of the truck so that when in place it will not overlie the upper edges of the side boards and thus provide ventilating spaces on the sides of body 1. If desired, the ends of the tilt or cover 2 may also lie within the ends, though I prefer that the reinforced ends may overhang the end boards, particularly when they are reinforced by inserted battens.

Before placing the tilt or cover in place, metallic strips 4, which may be flat bands, wires or hoops, are placed in engagement with the eye or hook 5, and the strand is passed therefrom upward, across and downward to engage the eye 5', this providing a series of transverse supports upon which the cover 2 is laid, and when the cover is in position the return strand is positioned to overlie the outer face of the cover. In practice, the ends will be drawn tight and made fast to the eye 5.

It will be noted that the tilt is supported by the inner cross strands and is held in place by the outer strands.

As the cover is supported at intervals, in case of rain or snow, excessive sagging of the cover will be prevented.

The cover sustaining and retaining means 5, 4, as well as the cover, are adapted for use and reuse, and it is within the scope of my invention to use any appropriate waterproof cover with the supporting and securing means.

10 What I claim is:—

1. A covering for bodies of vehicles comprising a sheet of material which is interposed between and is maintained by a plurality of spaced supports which are detachably connected to the body.

15 2. A tilt or covering for open trucks having a width less than the width of the body of the truck to provide open spaces between the margins of the tilt and the sides of the body, transverse underlying supporting and 20 overlying retaining means for the cover, which means span the spaces and are detachably connected to the opposite sides of the body of the truck.

25 3. A tilt for open body trucks comprising a flexible sheet covering of a waterproof and fireproof character, metallic means for associating the covering with the truck, said means consisting of spaced apart flexible 30 members between which the tilt is positioned, said members being held in engagement with eyes on opposite sides of the body of the truck.

In testimony whereof he affixes his signature.

LAURENS VAN HÜLST.
